Primary Examiner — Bridget L Eland*Assistant Examiner* — Lauren McVey(74) *Attorney, Agent, or Firm* — Muncy, Geissler, Olds & Lowe, P.C.(57) **CLAIM**

The ornamental design for a single port access platform, as shown and described.

DESCRIPTION

FIG. 1 is a front perspective view of a single port access platform according to the present invention.

FIG. 2 is a left side view of the single port access platform of FIG. 1.

FIG. 3 is a right side view of the single port access platform of FIG. 1.

FIG. 4 is a rear view of the single port access platform of FIG. 1.

FIG. 5 is a front view of the single port access platform of FIG. 1.

FIG. 6 is a top view of the single port access platform of FIG. 1; and,

FIG. 7 is a bottom view of the single port access platform of FIG. 1.

The broken lines that are immediately adjacent to the claim, and define unshaded regions, represent the bounds of the claim, while all other broken lines are directed to environment; the broken lines form no part of the claimed design.
